UNITED STATES PATENT OFFICE.

WILLIAM J. STEWART, OF WEBSTER, MASSACHUSETTS.

THIN-PLACE DETECTOR FOR LOOMS.

No. 895,591.

Specification of Letters Patent.

Patented Aug. 11, 1908.

Application filed January 22, 1906. Serial No. 297,181.

To all whom it may concern:

Be it known that I, WILLIAM J. STEWART, a citizen of the United States, residing at Webster, in the county of Worcester and 5 State of Massachusetts, have invented a new and useful Thin-Place Detector for Looms, of which the following is a specification.

In looms, particularly that class of automatic looms wherein the mechanism is arranged to provide a continuous supply of filling by automatically changing the shuttles or the bobbins in the shuttles, it frequently happens that owing to derangement in the weft supplying mechanism, the 10 loom will make a number of beats without any weft or filling being supplied. This will leave a thin place in the cloth which will cause imperfections and loss. This objection is especially found in the class of automatic looms, as each operator has to tend a large number of looms and very often these 15 thin places will occur and the loom again get into proper operation so that the thin place will escape detection. To overcome this 20 difficulty, I have provided a new and improved form of detector which is arranged to operate by electricity to stop the loom in case of failure of the filling supply. By providing electric controlling means to accomplish this purpose, I have found in practice 25 that a very efficient device can be provided.

The invention in the best form now known to me for putting the same into practice is shown in the two sheets of drawings forming 30 part of this application in which,

Figure 1 is a side elevation of enough of the parts of a loom to illustrate my invention. Fig. 2 is a plan view of part of the mechanism on an enlarged scale. Fig. 3 is a 35 side elevation of the feeler. Fig. 4 is a sectional elevation of the throw-out. Fig. 5 is a rear elevation of the throw-out, and Fig. 6 is a detail view of the switch controlled by the starting handle of the throw-out.

40 The improved detector comprises a feeler which bears on the cloth so that it will change its position in case of derangement in the supply of the filling, a throw-out for stopping the mechanism, an electro magnet 45 or armature attached to control the action

of the throw-out, and an electric circuit to the mechanism which is connected to be opened and closed by the feeler. A switch is also controlled by the starting handle of the throw-out so that the electric circuit is 55 only completed when the loom is in operation, thereby preventing short circuiting and waste of electricity.

The invention further consists of certain improved details of construction hereinafter 60 pointed out and described.

Referring to the drawings and in detail, A designates the frame, L the vibrating lathe, and B the breast-beam of the loom.

T designates the loom temple which is connected to the framing and arranged at the 65 side of the loom in the ordinary way.

A bracket 10 is secured to the loom frame and projecting from the same is a hub 11 of insulating material. Loosely pivoted on this hub is a feeler 12 which has a point which rests on the cloth just beyond the line where the filling is inserted. The feeler is arranged to strike on the projecting screw 13 of the 70 loom temple.

When the filling is properly supplied, the cloth will hold the feeler up, as shown in full lines in Fig. 3, but when the supply of filling is deranged, the point of the feeler will drop down into the cloth between the warp 80 threads and the feeler will rest on the screw 13 making an electric contact between the feeler and said screw.

A controlling handle 14 is pivoted to the loom frame at 15 and this handle is arranged 85 to actuate a pivoted arm 16 which is connected to control the clutch by which power is imparted to the loom. The controlling handle 14 works in a slot 17 formed in a guide 18 secured to the loom frame. Said slot is 90 provided with a notch 19 so that the controlling handle 14 can be left in position to keep the loom in operation.

A spring or other device is arranged in the ordinary way so that the normal tendency of 95 the controlling handle 14 will be to shift to the left, as shown in Fig. 5, so as to throw the loom out of operation.

A throw-out device is arranged to control the operating handle 14. This throw-out de- 100

vice consists of a lever 20 which is pivoted to the loom frame at 21. A dog 22 is pivoted on the lower end of this lever 20. A bunter 23 is arranged on the lathe of the loom. An 5 electro magnet 24 is secured in a box fastened on the inside of the frame, as shown. An armature 25 is pivoted in this box so as to be actuated by said magnet.

The armature is connected by a link 26 to 10 the pivoted dog 22. The parts are shown in normal position in Fig. 1, in which position the pivoted dog 22 comes below the bunter 23 on the lathe so that the bunter will clear said dog as the lathe beats up the filling. An 15 arm 27 is pivoted on a stud 28 in the lower part of the loom frame. The top face of the arm is inclined, as shown, and is provided with a slot. The controlling handle 14 is extended down below this pivot 15, as at 140 20 and this extension 140 fits in said slot 29.

30 designates one leading-in wire of the electric circuit.

From the electro magnet a wire 31 is lead 25 to a spring 32 mounted on a board 33 which is made out of insulating material. These parts are arranged in position so that when the controlling handle 14 is moved to the position shown in Fig. 5 to put the loom into 30 operation, the lower end 140 thereof will move outwardly in the slot 29 of the arm 27 and will slightly throw the arm 27 to the rear of the loom and into contact with the spring 32. This will connect the leading-in wire 30 35 electrically to the loom frame. Another leading-in wire 34 is connected to the feeler 12. The wires 30 and 34 are connected to a suitable source of electric energy.

In operation, when the loom is thrown 40 into operation, the wire 30 will be electrically connected to the loom frame, as previously described. So long as there is proper filling in the cloth, the feeler will be kept out of contact with the screw 13. When there is a 45 derangement in the supply of the filling, the feeler will drop down into the cloth and will come in contact with the screw 13. This will complete the circuit and will energize the electro magnet 24. This will pull down the armature 25 and will move the pivoted dog 22 so that on the next beat of the lathe, the 50 controlling handle 14 will be moved out of its notch 19 thereby allowing the same to spring to the left, as shown in Fig. 5, and thus stop the loom.

When the loom is stopped, the arm 27, which thus practically performs an electric switch, will be moved out of contact with the spring 32. This will break the electric circuit 60 and will prevent a waste of electricity after the loom has been thrown out of operation, and also will prevent short circuiting when the loom is not in operation.

By the mechanism thus described, a simple and efficient apparatus for the purposes 65 stated is provided.

Having thus fully described my invention, what I claim and desire to secure by Letters-Patent is:—

1. A thin place detector for looms comprising a feeler bearing on the cloth so as to change its position in case of derangement of filling, a controlling handle for the loom, a throw-out for stopping the loom, an electro magnet and armature adapted to control the 75 action of the throw-out, an electric circuit connected to the magnet and to be opened and closed by the feeler, a switch, and means controlled by the operation of the starting handle for operating said switch. 80

2. The combination of a loom, a feeler arranged thereon so as to engage the loom temple and normally held out of engagement therewith by the filling in the cloth, a throw-out for stopping the loom, an electro magnet 85 and armature attached to control the action of the throw-out, and an electric circuit connected to the magnet to be closed and opened by the feeler engaging and disengaging the loom temple. 90

3. The combination with a loom having a temple, of a feeler adapted to engage the temple and arranged to be held out of engagement therewith by the cloth, and electric connections for stopping the loom when 95 the feeler engages the temple.

4. A thin place detector for looms, comprising a feeler adapted to bear on the cloth and to change its position in case of derangement of the filling, an electric circuit adapted to be closed by the falling of the feeler, means connected with said circuit for stopping the loom when the circuit is closed, a switch in said circuit and means controlled by the stopping of the loom for turning said 105 switch to again open the circuit. 100

5. A thin place detector for looms, comprising a feeler adapted to bear on the cloth and to change its position in case of derangement of the filling, an electric circuit adapted to be closed by the falling of the feeler, means connected with said circuit for stopping the loom when the circuit is closed, and a switch in said circuit adapted to be turned by the stopping of the loom to again open the 115 circuit, said switch comprising a pivoted arm having a cam slot which the loom stopping mechanism is adapted to move. 110

6. A thin place detector for looms comprising a feeler bearing on the cloth so as to 120 change its position in case of derangement of filling, a throw-out for stopping the loom, a controlling handle, an electro magnet and armature attached to control the action of the throw-out, an electric circuit connected 125 to the magnet and to be opened and closed

by the feeler, and a switch in said circuit comprising a pivoted arm having a cam slot with which the controlling handle engages.

7. A thin place detector for looms comprising an insulated bearing carried by the loom, a feeler pivoted on the insulated bearing and bearing on the cloth so as to change its position in case of derangement of filling, a throw-out for stopping the loom, an electro 10 magnet and armature attached to control

the action of the throw-out, and an electric circuit connected to the magnet to be opened and closed by the feeler.

In testimony whereof I have hereunto set my hand, in the presence of two subscribing 15 witnesses.

WILLIAM J. STEWART.
